TUBE CONTENT DISPENSER

Stanley Gelb, Wyndmoor, Pa., assignor to Gell Corporation, Philadelphia, Pa., a corporation of Pennsylvania

Filed Nov. 30, 1960, Ser. No. 63,036

Term of patent 14 years

(Cl. D4—3)

FIG. 1.

FIG. 4.

FIG. 3.

FIG. 2.

FIG. 1 is a front perspective view of a tube content dispenser showing my new design; the additional matter shown in dotted lines is for illustrative purposes only;

FIG. 2 is a side elevational view thereof, the opposite side being substantially the same in appearance;

FIG. 3 is a front elevational view; and

FIG. 4 is a top plan view.

I claim:

The ornamental design for a tube content dispenser, as shown and described.
